TOOL RETAINER

John H. Parsons, Bloomfield Hills, and Lawrence
S. Lamb, Grosse Pointe Park, Mich.Application October 31, 1932, Serial No. 640,466
Renewed July 9, 1937

12 Claims. (Cl. 164—118)

This invention relates to tool-retaining devices, such as are commonly used to retain punches, dies, drills and the like in their holders. It is usually desired that tools of this class be interchangeable in their holders, and various means have in the past been employed to removably secure them. Such previously used retaining means have been unsatisfactory for a number of reasons. Those so designed as to retain the tools with adequate firmness necessitated the expenditure of too much time and trouble in attaching and removing the tools, while many of those designed to permit rapid interchanging of the retained tools have not provided adequate security. Some such retainers designed for quick action provide adequate security for circular punches, for example, but not for punches and dies of irregular contour, or for drills or other rotating tools. Other quick action retainers do not prevent lengthwise movement of the retained tool in the holder, although adequately locking it against rotative movement, which is also undesirable.

In other interchangeable retaining systems the shanks of the tools must be provided with a depression or depressions of special or elaborate configuration requiring special milling cutters or grinding wheels to form, so that prospective users far from a source of supply of tools having such shanks frequently dare not employ them, as in order to do so safely they would have to carry on hand a prohibitively expensive reserve supply, or special cutting or grinding equipment, to prevent the danger of a tool breakage stopping production.

The primary object of the present invention is to provide a tool retainer subject to none of the foregoing briefly summarized shortcomings and defects, and which, while permitting instantaneous removal and insertion of a tool in the retainer, retains the tool with such firmness as to prevent any possibility of either rotative or endwise movement of the tool with respect to the retainer.

Another object of this invention is the production of such a retainer which is of simple and inexpensive construction, and which is utilizable in conjunction with tools and holders of conventional designs now in use, merely necessitating slight alterations thereof, to effect which alterations special machinery is not required.

A further important object is the provision of such retaining means installable in less space than those heretofore used, and without regard to the relative hardnesses of the metal in which

the tool shank and the retainer itself are installed.

Another object is the provision of an improved tool retainer so designed that the retainer block need not be specially hardened.

Another important object is the incorporation in such a retainer construction of indicating means enabling easy determination by the operation as to whether or not the tool is properly locked in the retainer.

A still further object is the provision of improved pilot means insuring insertion of the tool in the retainer in the proper manner.

Another object is the provision of an improved retainer block construction enabling mounting interchangeably retained tools on closer centers.

Another object is the provision of means for interchangeably mounting a series of tools in an elongated retainer without the necessity of regrinding each tool socket or other aperture after a hardening operation to correct inaccuracies so introduced, but in which an unhardened retainer is used with inserted sockets or the like individually hardened, together with improved means for supporting tools of unusual length.

Other objects and advantages will be apparent from the following description wherein reference is made to the accompanying drawings illustrating preferred embodiments of our invention, and wherein similar reference numerals designate similar parts throughout the several views.

In the drawings:

Figure 1 is a vertical sectional view taken substantially longitudinally through a punch retainer incorporating the principles of our invention, showing a punch secured therein, and also fragmentarily showing a punch holder, stripper plate, a piece of sheet stock being worked upon, and a die;

Figure 2 is a top plan view of the punch retainer removed from the backing plate and punch holder, taken substantially on the line 2—2 of Figure 1 and looking in the direction of the arrows;

Figure 3 is a fragmentary top plan view with the backing plate in place, taken as if on line 3—3 of Figure 1;

Figure 4 is a fragmentary top plan view of the punch and detent;

Figure 5 is a fragmentary detail section similar to Figure 1 in the parts shown, but illustrating the punch released, or before being secured;

Figure 6 is a similarly taken fragmentary sec-

tion of a somewhat modified punch retainer installation incorporated with a sheet metal shearing device also fragmentarily shown with a piece of stock being worked upon;

5 Figure 7 is a similar sectional view of another modified form showing novel means for supporting unusually long tools, together with a novel piloting device carried by the stripper plate;

10 Figure 8 is a top plan view of a plurality of 10 retainers of this form arranged in series, showing the holder in one instance prepared for the retainer and tool which are not yet installed;

15 Figures 9 and 10 are top and side views respectively of the tool socket bushing;

20 Figure 11 is a top plan view, also with the backing plate removed, of another series-mounting arrangement for punches, four of which are shown installed;

25 Figure 12 is a top plan view of a plurality of 20 our improved retainer blocks of different sizes arranged in interfitting relation; and

30 Figure 13 is a similar view showing another arrangement.

35 Referring now to the drawings: Reference character 20 represents the main block or body of a punch retainer, utilized as illustrative of a typical application of our invention. A cylindrical bore 21 is formed therein adapted to receive a punch shank, as the shank 22 of the punch 23. 40 A transverse groove is formed in and adjacent the upper end of the shank of the punch, as indicated at 24, Figures 1 and 5. The preferred form of this groove is clearly shown in the drawings, from which it will be observed that a generally plane angularly arranged surface 24' 45 forms its upper wall. The top edge of the punch may also be chamfered, as at 25, to facilitate its insertion in the retainer.

50 A depression is formed in the top of the retainer block 20 adjacent the upper extremity of the tool shank socket 21. This depression may take the form of a simple milled slot 26 disposed transversely of the block, as shown in Figures 1 and 2. Terminating in the slot 26 and vertically arranged beside the punch socket 21 is a bore 27 having a reduced upper portion 28. Vertically reciprocable in the aperture 27-28 is a stem 29, carrying a cupped collar and spring abutment member 30 at its lower extremity which is of such size as to slidably fit within the larger portion 27 of the vertical aperture and may extend downwardly from the open lower end of the aperture to form a plunger for convenient manipulation. The body of the pin 29 slides in the upper reduced portion 28 of the aperture, and the compression spring 31 housed within the larger portion 27 of the aperture encircling the pin, and in the cupped member 30, seats at its upper end against the shoulder formed by the reduced portion 28 of the aperture and bears at its other end against member 30 to urge the pin downwardly. Secured to the upper extremity of the pin and arranged transversely thereof is the wedging cam member 32, which is housed within the depression formed by the slot 26, and of course also serves as a stop to limit downward movement of the pin 29. Also within the depression formed by the slot 26, slidably fitting between the backing plate and the bottom of the slot and arranged between the wedging member 32 and the punch socket 21, is the locking detent 33, the central portion of which, since the punch socket and the depression 26 intersect, normally projects into the socket, being forced thereinto by the cam-like action of the wedge 32 as the latter is forced downwardly

under the influence of the spring 31. In order to position the detent 33 and prevent its sliding from the recess 26, it may be formed with rearwardly projecting ends 34 engaging the sides of the wedge 32, as shown in Figures 2 and 3. The locking surface 35 of the detent may be partly cylindrical, so that it contacts the locking surface 24' of the punch shank groove along a straight line, and the lower surface of the detent which overhangs the socket may be angularly cut out, as at 36, to form a cam surface engageable by the chamfered upper end of the punch shank by which the detent may be forced clear of the socket as the punch is inserted when the wedge is released.

15 The angle between the wedge member 32 and the rear face of the detent 33 is such that the wedge cannot be forced upwardly by pressure in the direction of the arrow 37 exerted through the detent. While as above pointed out, the surface 32' of the wedge 32 and the rear surface 33' of the detent 33 are arranged at a wedging angle, so that the wedge cannot be urged upwardly by lateral pressure exerted through the detent, the inclined engaging surface 24' of the punch shank 25 aperture is not arranged at a locking angle relatively to the portion of the locking surface 35 of the detent it engages, so that when the detent is released by upward movement of the wedge member, a retained tool may be removed from the 30 socket by merely pulling the same downwardly, the detent member being thereby forced laterally in the direction of arrow 37 and out of the tool socket. The wedge is moved upwardly by pushing upwardly upon the plunger 30, either manually, or if it is inaccessible, by means of a suitable tool (not shown). The plunger, of course, may or may not project from its aperture 27, depending upon the clearance available in the particular tool installation. If the plunger cannot project, 40 any pointed or suitably sized member may be inserted in the aperture to enable forcing the plunger inwardly. In order to permit insertion of the punch the detent is first released, so that it is free to move laterally, by pushing the wedge 45 32 and associated parts upwardly, after which the shank of the punch may be inserted in the socket, the chamfered surfaces 25-36 cooperating to force the detent out of the socket, permitting full insertion of the tool, after which release of the 50 upward pressure against the plunger 30 permits the wedge 32 to move downwardly, forcing the detent 33 back into the punch socket, and into engagement with the slot 24 in the punch shank. The tool is thereupon locked against removal, 55 since no amount of force in the direction 37 generated by downward pull upon the tool is sufficient to force the wedge 32 upwardly. It will be noted that the engagement of the locking surface 35 of the detent with the inclined surface 24' 60 of the punch shank slot tends to force the punch upwardly within its socket, and thus maintains the top of the punch in engagement with the top of the socket, preventing longitudinal reciprocation or "slopping" of the punch shank in the 65 socket, which might, upon subjection of the tool to hard and rapid usage, result in peening of the upper end of the punch shank, or crystallization of the metal subjected to the percussion thus generated. The top of the punch socket and retainer recess 26 may if desired be closed by a 70 backing plate, as 39, secured to the top of the plate 20 in any suitable fashion, as by the same screws 40 which secure the retainer block to the punch holder 41. In the backing plate is formed 75

a clearance slot or aperture 42 wherein the wedge member 32 is permitted to move upwardly, as shown in Figure 5.

Preferably the shank of the tool is flattened as at 43 immediately above the locking slot, and the detent is movable rearwardly only far enough to permit full insertion of the tool when this flat 43 is aligned with the detent, which thus also serves as a pilot preventing improper insertion of the tool with the locking groove disaligned with the detent.

Although only parts of the illustrative punch press appear in the drawings, it will be seen that in Figure 1 a "button" die is shown arranged for cooperative reception of the punch. The die, whether of this or any other removable type, may of course also be positioned by one of our improved retainers, although a showing thereof is not included, inasmuch as it would serve merely to unnecessarily elaborate the drawings.

It will be seen that close size limits need not be observed in forming the locking parts or the apertures in which they move, and that the detent 33, wedge 32 and rod 29 may be formed of bar stock which is rolled in manufacture to the desired cross section, and then cut off to the desired lengths. The retainer block 20 may be of low carbon steel, which is copper-plated before final reaming of the punch socket 21 and detent slot 26, after which it may be case-hardened upon only these surfaces from which the copper-plating has been removed. The apertures 44 are preferably of reamer drill size, and the block being unhardened, it may in assembly upon the tool be positioned upon the punch holder, the holes drilled in the latter by means of a full sized drill, using the block as a template, and both apertures then reamed at once, thus making disalignment virtually impossible.

By reason of the lateral engagement of the rearward extensions 34 of the detent with the sides of the wedge member, the detent is positively positioned against lateral displacement without the necessity of employing any other guides except the backing plate and the bottom of the slot 26. Thus the slot may be opened at its ends, and thus also a plurality of detents and wedge members may be arranged in a single elongated slot when a series of punches is employed. Note in this connection the typical series arrangement shown in Figure 8, in which the single elongated slot 26³ is designed to accommodate a plurality of detents 33³ and interfitting wedge members 32³, the former of which engage a plurality of punches as 23³ having their sides carrying the retaining grooves exposed to the slot. The series arrangement shown in this view will presently be described in greater detail.

In Figure 6 is shown an illustrative embodiment typifying the ease with which our improved retainer is installable in tool assemblies now considered impossible of adaptation to interchangeable retainers. In this construction, which will be recognized as typical, a forming or shearing blade 45 is carried by the press adjacent the punch 23², the punch retainer block 20² being thereby necessarily limited in size. If, as in the construction shown, one of the securing screws as 40² lies immediately behind the punch, it becomes a difficult matter to install an interchangeable retainer of any of the types now known, as if an attempt is made to put ordinary retainers in the body of the blade member 45 in the manner in which our improved retainer is shown installed, the differences of hardness of the metals of the

shearing blade and the retainer block, through the thin wall of which between the blade and punch shank the detent must project, make it impossible to hold the aperture through which the detent works to close limits, or to hold the two sections of the aperture in exact alignment. If then the design of the interchangeable retainer is such as is commonly the case, that the detent and its aperture must fit to close limits, such an installation is impossible. With our improved construction on the other hand, the detent works through what may be termed a clearance slot only. The size limits of these parts are relatively unimportant and need not be close. The locking means may be installed in the body of the blade in the manner shown in Figure 6, with the detent member 33² projecting through an aperture (undesignated) in the front of the block 20². The plunger 30² by means of which the punch is released is then also easily accessible from the front of the tool, making this a desirable method of installation even though there might be room for the retainer in the block 20² behind the punch. Analogous parts to those shown and described in connection with the first embodiment will be seen to have been given like reference numerals with the addition of prime exponents. Their similar functioning will be easily understood, and detailed repetition of the description of these parts will accordingly be omitted as unnecessary.

Figure 7 shows another somewhat modified form particularly adapted for use in connection with long punches which project farther from the holder than is usual. Such a punch is shown at 23³. In this embodiment the punch socket is formed of an individually hardened and ground bushing 21³ which may be press fitted in the unhardened retainer block 20³ and provided with a flange as 46 at its upper end which serves to additionally position it when clamped beneath the backing plate 38³ upon assembly of the retainer upon the punch holder in the manner shown. The socket bushing 21³ projects downwardly from the retainer block to form a support for the elongated punch shank, as clearly shown in the drawings. The top of the socket bushing is cut away as at 47 (Figures 9 and 10) to permit the detent member 33³ to enter the locking groove 24³ in the tool shank. If a stripper plate as 48 which is rigidly fixed to the bed or table of the machine is employed, it may carry a pilot bushing as 49 adapted to serve as a guide for the socket bushing 21³, to properly align the punch with the die 50, and thus prevent damage to either in event of any sloppiness in the punch holder—a common condition. The remaining analogous parts have been given like reference numerals with cube exponents.

As shown in Figure 8, the socket bushings 21³ form a convenient means whereby a number of punches may be arranged in an elongated series in a retainer bar as 20³ which may be of unhardened metal. At the present time great difficulty is encountered in arranging a long series of punches in a single bar carrying interchangeable retainers for cooperation with a similarly arranged series of dies which are usually also mounted in an elongated bar, as after drilling the socket holes the bars must be hardened, throwing the punch and die sockets in their respective bars out of alignment, and each punch and die socket must then be individually ground and by such grinding aligned with the opposed socket in the other bar—a slow and expensive

operation. With the improved construction shown, on the other hand, the punch retainer bar may be left unhardened and the holes for the socket bushings 21^3 drilled upon proper centers, the bushings which are of course previously hardened and ground, (a simple production operation upon such pieces) are then press fitted into the bar, which is then completed insofar as the arrangement of the punch sockets therein is concerned. The die bar is of course similarly formed, and it will be understood that the same retaining means is preferably employed in conjunction with the dies (and that it is equally adaptable to other tools as well). The detent members as 33^3 and wedges as 32^3 may be housed in a single elongated slot 26^3 traversing the bar.

As indicated in Figure 11, more than one tool as 23^4 may be held by a single detent, as 33^4 , and punches, for example, may in this manner be positioned as close together as desired, or as the walls between the die sockets will permit. The punch shanks may even be somewhat flattened on their meeting sides to permit closer spacing if desired.

Our preferred contouring of the assembled retainer blocks and backing plates is best brought out in plan view Figures 12 and 13, showing typical nestings of punch retainers of various sizes, and bringing out the manner in which their shaping permits arrangement of a plurality of punches on close centers though mounted in standardized retainers. As shown in Figure 12 the nose of each retainer block as 20^5 is rounded concentrically about the axis of the punch socket 21^5 , and is filleted or flared outwardly as at 53 to meet the side walls of the retainer only at a point well back of the nose of the block and punch axis. This back radius of the flare is preferably greater than the nose radius of the largest block, which assists the interfitting of the retainers, as shown, with a minimum spacing less than is ordinarily obtainable.

While it will be apparent that the illustrated embodiments of our invention herein disclosed are well calculated to adequately fulfill the objects and advantages herein stated, it is to be understood that the invention is susceptible to variation, modification and change within the spirit and scope of the subjoined claims.

What we claim is:

1. In a tool retainer, a block member having a tool socket therein and a depression in its rear surface adjacent and intersecting the socket, a backing plate arranged over the depression, a detent member slidable in the depression between and confined by the bottom of the latter and the backing plate which thus cooperate to form a slideway, said detent member having an inclined rear surface, an actuating member for the detent member movable laterally of the path of movement of the detent member having a wedging portion within the depression engageable with said inclined rear surface of the detent.

2. In combination with a tool having a shank, a transverse slot in the shank and a flat surface above the transverse slot and extending the entire distance to the end of the shank, a retainer including a retainer block having a socket therein adapted to receive the tool shank, a detent carried by the block and movable inwardly and outwardly of the socket but not completely therefrom, the detent being arranged to project into the socket when retracted to the limit of its travel a sufficient distance to prevent full insertion of the tool except with the flat surface

thereof abutting the detent, and being adapted when the tool is so fully inserted and the detent is projected to engage in the slot in the tool shank.

3. In a metal forming device, a holder, a blade-like forming member carried thereby, a tool retainer block carried by the holder adjacent the blade and having a tool socket therein, a channel formed of registering openings in the blade member and retainer block, and tool locking means carried by the blade member and including a detent in the channel movable inwardly and outwardly of the socket.

4. In combination with a tool having a transversely slotted shank, a tool retainer comprising a member socketed to receive the tool shank, a detent member projectable into the socket to engage the slot in the tool shank and movable therefrom to release the same, a wedging member arranged substantially behind the detent member for locking the detent member in projected position, and means for moving the wedge member to lock or release the detent at will, the slotted area of the tool shank engaged by the detent being disposed at a large angle relatively to the tool socket, whereby the detent urges the tool farther in the socket as the detent is forced toward the shank.

5. In combination with a tool retainer having a socket therein, a tool having a shank insertable in the socket, the shank being provided with a transverse depression having an inclined face arranged at a large angle relatively to the shank, a detent member having a portion curved about an axis transverse to that of the socket and projectable into the socket for cooperative engagement with the inclined face of the depression in the shank, whereby the detent engages the tool shank along a transverse line, and upon being urged thereagainst urges the tool shank inwardly of the socket.

6. In a tool retainer, a block member having a tool socket therein and a depression in its rear surface adjacent and intersecting the socket, a backing plate arranged over the depression and having an aperture therein also overlying part of the depression, a detent member in the depression confined by the bottom thereof and by the backing plate and slidably therebetween and inwardly and outwardly of the tool socket, and an actuating member for the detent movable transversely of the groove and backing plate and in the aperture in the latter.

7. In combination with a tool having a shank, a depression in the side of the shank, and a longitudinally arranged guiding portion carried by the shank and extending from the depression to its end, a retainer comprising a block having a tool socket therein, a detent carried by the block and movable inwardly and outwardly of the socket but having a portion adapted to project partially into the tool socket when the detent is fully retracted and engageable with the guiding portion of the tool shank while the tool is being inserted to prevent insertion of the tool except with such surfaces in desired relation.

8. In a metal forming device, a holder, a blade-like forming member carried thereby, a punch, and means for removably supporting the punch in the holder, comprising a retainer carried by the holder having a socket therein for the punch and arranged adjacent the blade, the blade member and retainer having aligned apertures therein forming a channel intersecting the socket, and punch locking means including a detent movable

in said channel in and outwardly of the socket and operable from the opposite side of the forming member to that occupied by the socket.

9. In combination with a tool having a shank and a transverse slot in the shank, a tool retainer comprising a member socketed to receive a tool shank, a detent member projectable into the socket to engage an upper surface of the slot in the tool shank, a wedging member for maintaining the detent in projected position, said upper surface of the slot in the tool shank being arranged at less than a wedging angle with respect to the direction of projection of the detent member, whereby the engagement of the detent and said surface of the slot in the tool shank urges the tool inwardly of the socket as the detent is urged toward the shank, and means for releasing the wedge member.

10. Means for removably supporting a plurality of tools, comprising an elongated retainer having a plurality of tool sockets therein and extending substantially therethrough, a channel extending along the opposite surface of the retainer from which the tools are intended to project and intersecting the sockets, a plurality of detents arranged in the channel and so movable transversely thereof that one may be projected laterally into and substantially withdrawn from each socket, an actuating cam member arranged behind each detent, means for moving the cam

members to force the detents into the sockets, and engaging portions carried by the cam members and detents adapted to prevent displacement of the detent members along the channel without preventing the described actuating movement of the detents.

11. In a tool retainer having a socket therein and a channel transversely intersecting the socket and wider than the maximum width of that part of the socket which it intersects, a detent member slidable in the channel toward and from the axis of the socket and so inwardly and outwardly thereof, said detent extending into said portions of the channel wider than the intersected part of the socket and being supported by said portions when projected into the socket.

12. In a tool retainer having a socket therein, a detent member having a portion curved about an axis transverse to the socket and projectable thereinto, said detent having a supporting base portion projecting at either end beyond the intersected portion of the socket and within the peripheral line thereof when viewed from the side, said detent having a substantially flat inclined rear surface, and a wedging cam arranged behind the detent and having a similarly inclined flat surface in engagement therewith.

JOHN H. PARSONS.
LAWRENCE S. LAMB. 30
